(57) **ABSTRACT**

A removable crossbar assembly and an exercise ladder arrangement including the removable crossbar assembly. The crossbar assembly is configured to be secured to an exercise ladder to provide an exercise crossbar disposed between two fixed exercise crossbars on the exercise ladder. The crossbar assembly includes first and second securement flaps that restrict vertical movement of the crossbar assembly during use.

CROSSBAR ASSEMBLY FOR AN EXERCISE LADDER AND AN EXERCISE LADDER ARRANGEMENT INCORPORATING SAME

FIELD

This disclosure relates to the field of exercise devices, particularly to ladder-type exercise devices and their accessories.

BACKGROUND

A variety of exercise devices are used to strengthen the body and/or to improve balance, etc. Some exercise devices include an exercise ladder having spaced-apart vertical supports and a plurality of horizontal exercise ladder cross-bars (e.g., rungs) between the supports that are vertically spaced-apart. See, for example, U.S. Pat. No. 7,931,570 by Hoffman, which is incorporated herein by reference in its entirety and attached hereto.

One problem associated with such devices is that many exercises require the participant to hold onto or otherwise utilize a crossbar on the ladder that is very closely matched to a point on a participant's body, e.g., a crossbar that is about the same height as the participant's shoulders. However, such exercise ladders typically utilize permanently mounted crossbars that are spaced apart at a regular distance, such as about 8 inches apart. Thus, while a particular crossbar may be properly positioned for a participant having a shoulder height closely matching the height of a crossbar, many participants will be forced to use a crossbar that is not closely aligned with their shoulder height, thereby diminishing the efficacy of the exercise.

A removable crossbar assembly to address these issues is disclosed in US Patent Publication No. 2022/0288437 by Geissler et al., which is incorporated herein by reference in its entirety. This patent publication discloses a removable crossbar assembly that advantageously enables a participant to perform an exercise using the crossbar assembly in a position (e.g., at a height) that would not otherwise be obtainable using the permanent (e.g., fixed) rungs on the exercise ladder.

SUMMARY

It is an objective of the present disclosure to provide a removable crossbar assembly for use with an exercise ladder, wherein the crossbar assembly may be secured to the exercise ladder with minimal movement of the exercise assembly during use.

In one embodiment, a removable crossbar assembly is provided. The crossbar assembly includes first and second horizontally spaced-apart brackets that are configured to be attached to an exercise ladder. The first and second brackets each comprise a planar body having an inner surface and an outer surface, each surface bounded by a top edge, a bottom edge, a front edge and a back edge. A lower vertical support notch is formed in each planar body and is configured to operatively receive a first exercise ladder crossbar therein. An upper vertical support notch is formed in each planar body, above and substantially vertically colinear with the lower vertical support notch and is configured to receive a second exercise ladder crossbar therein. An exercise assembly crossbar extends from the first bracket to the second bracket. The exercise assembly crossbar is affixed to each of the first and second brackets between the lower vertical support notch and the upper vertical support notch. The

2

assembly also includes a first securement flap pivotally connected to the first horizontally spaced-apart bracket planar body and comprising a first securement notch disposed in a top edge of the first securement flap, wherein the first securement notch is configured to operatively engage an exercise ladder crossbar when the first securement flap is pivoted upwardly. A second securement flap is pivotally connected to the second horizontally spaced-apart bracket planar body and comprises a second securement notch disposed in a top edge of the second securement flap, wherein the second securement notch is configured to operatively engage the exercise ladder crossbar when the second securement flap is pivoted upwardly.

The foregoing crossbar assembly is subject to a number of characterizations and refinements that may be implemented individually or in any combination. In one characterization, the lower vertical support notches are formed in the bottom edge of the planar bodies. In another characterization, the upper vertical support notch is accessed through a gap formed in a back edge of the planar bodies to enable the second exercise ladder crossbar to be placed through the gap and into the upper vertical support notch. In another characterization, the exercise assembly crossbar is affixed to the brackets at a point approximately on-half the distance between the upper vertical support notches and the lower vertical support notches. In another characterization, the crossbar assembly further comprises a horizontal plank extending from the first bracket to the second bracket, where the horizontal plank is affixed to each of the first and second brackets near the top edge and the back edge of the first and second brackets.

In another characterization, each of the first and second brackets further comprises a brace extending outwardly from the front edge of the planar body, the brace comprising an exercise equipment receiving notch configured for receiving and securing an additional piece of exercise equipment to the assembly. In one refinement, the exercise equipment receiving notch is disposed in a top edge of the brace. In another refinement, the exercise equipment receiving notch is spaced away from the front edge of the first and second brackets. In another refinement, the equipment receiving notch is substantially vertically coplanar with the exercise assembly crossbar.

In another characterization, first and second securement flaps are pivotally connected to the top edges of the first and second horizontally spaced-apart bracket planar bodies respectively. In one refinement, the first and second securement flaps are pivotally connected to the top edges of the first and second horizontally spaced-apart bracket planar bodies respectively using at least a first barrel hinge.

In another embodiment, an exercise ladder arrangement is provided. The exercise ladder arrangement comprises an exercise ladder having first and second spaced-apart vertical supports and a plurality of exercise ladder crossbars, e.g., at least about three exercise ladder crossbars, affixed to the first and second vertical support and extending therebetween. A crossbar assembly is removably secured to the exercise ladder. The crossbar assembly comprises first and second horizontally spaced-apart brackets. The brackets each comprise a planar body having an inner surface and an outer surface, each surface bounded by a top edge, a bottom edge, a front edge and a back edge. The brackets each comprise a lower vertical support notch operatively securing a first exercise ladder crossbar therein, and an upper vertical support notch formed in the planar body, above and substantially vertically colinear with the lower vertical support notch, and securing a second exercise ladder crossbar

therein. An exercise assembly crossbar extends from the first bracket to the second bracket, where the exercise assembly crossbar is affixed to each of the first and second brackets. A first securement flap is pivotally connected to the first horizontally spaced-apart bracket planar body and comprises a first securement notch disposed in a top edge of the first securement flap, wherein the first securement notch is configured to operatively engage a third exercise ladder crossbar when the first securement flap is pivoted upwardly. A second securement flap is pivotally connected to the second horizontally spaced-apart bracket planar body and comprises a second securement notch disposed in a top edge of the second securement flap, wherein the second securement notch is also configured to operatively engage the third exercise ladder crossbar when the second securement flap is pivoted upwardly.

The foregoing exercise ladder arrangement is subject to a number of characterizations and refinements that may be implemented individually or in any combination. In one characterization, the exercise assembly crossbar is affixed to each of the first and second brackets at a point approximately one-half the distance between the lower vertical support notch and the upper vertical support notch. In another characterization, the exercise ladder arrangement further comprises a horizontal plank extending from the first bracket to the second bracket, where the horizontal plank is affixed to each of the first and second brackets near the top edge and the back edge of the first and second brackets. In another characterization, the exercise ladder arrangement further comprises at least first and second securement straps securing the attachment exercise crossbar to the first exercise ladder crossbar to deter vertical movement of the removable attachment. In one refinement, the securement straps comprise a hook and loop fastener.

In another characterization, each of the first and second brackets further comprises a brace extending from the front edge of the planar body, the brace comprising an exercise equipment receiving notch disposed therein. In one refinement, the exercise equipment receiving notch is disposed in a top edge of the brace. In another refinement, the exercise equipment receiving notch is spaced away from the front edge of the first and second brackets. In another refinement, the exercise equipment receiving notch is substantially vertically coplanar with the attachment exercise crossbar. In another characterization, the exercise ladder arrangement includes at least a first spacer element disposed on at least one of the first and second exercise ladder crossbars between the vertical ladder support and the removable exercise assembly.

DESCRIPTION OF THE DRAWINGS

FIG. 1 illustrates a perspective view of a removable crossbar assembly for an exercise ladder according to an embodiment of the present disclosure.

FIGS. 2A and 2B illustrate end views of a removable crossbar assembly for an exercise ladder according to an embodiment of the present disclosure.

FIG. 3 illustrates a front view of a removable crossbar assembly for an exercise ladder according to an embodiment of the present disclosure.

FIG. 4 illustrates a removable crossbar assembly that is secured to an exercise ladder according to an embodiment of the present disclosure.

FIG. 5 illustrates a removable crossbar assembly that is secured to an exercise ladder according to an embodiment of the present disclosure.

FIG. 6 illustrates a partial view of a removable crossbar assembly that is secured to an exercise ladder according to an embodiment of the present disclosure.

FIG. 7 illustrates a removable crossbar assembly for an exercise ladder according to an embodiment of the present disclosure.

FIGS. 8A and 8B illustrate side views of a removable crossbar assembly for an exercise ladder according to an embodiment of the present disclosure.

FIG. 9 illustrates a removable crossbar assembly for an exercise ladder according to an embodiment of the present disclosure.

FIG. 10 illustrates a removable crossbar assembly that is secured to an exercise ladder and supporting an exercise device according to an embodiment of the present disclosure.

DESCRIPTION OF THE EMBODIMENTS

FIGS. 1 to 3 illustrate several views of a removable crossbar assembly for an exercise ladder according to an embodiment of the present disclosure. FIG. 1 is a perspective view of a removable crossbar assembly, FIGS. 2A and 2B illustrate two side (e.g., end) views of a removable crossbar assembly, and FIG. 3 illustrates a front view of a removable crossbar assembly.

Referring to FIGS. 1 to 3, the removable crossbar assembly 110 includes a first bracket 120A and a second bracket 120B that is spaced away from (e.g., horizontally spaced-away from) the first bracket 120A. The brackets 120A/120B are configured to be operatively secured to an exercise ladder (e.g., as in FIGS. 4 to 6). Specifically, as illustrated in FIGS. 1 to 3, the brackets 120A/120B each include a planar body 122A/122B having notches or a similar feature to facilitate the secure attachment of the assembly 110 to an exercise ladder. Each of the planar bodies 122A/122B includes an inner surface 124A/124B and an outer surface 126A/126B bounded by a top edge 128A/128B, a bottom edge 130A/130B, a front edge 132A/132B and a back edge 134A/134B. A lower vertical support notch 136A/136B is formed, e.g., in each of the bottom edges and each notch is configured (e.g. sized and shaped) to receive a first (lower) exercise ladder crossbar within the lower notch 136A/136B. An upper vertical support notch 138A/138B is formed in each planar body, above and substantially vertically colinear with the lower vertical support notch 136A/136B, as shown in FIGS. 2A and 2B. The upper vertical support notches 138A/138B are configured (e.g., sized and shaped) to receive a second exercise ladder crossbar therein, e.g., a second exercise crossbar that is adjacent to and spaced apart from (e.g. vertically spaced above) the first exercise ladder crossbar. A gap 140A/140B is formed in the back edge 134A/134B of the planar body and provides access to the upper vertical support notch 138A/138B to enable the second exercise ladder crossbar to be placed through the gap 140A/140B and into the upper vertical support notch 138A/138B, e.g., without necessitating removal of a crossbar from the exercise ladder.

An exercise assembly crossbar 142 extends across the assembly, e.g., extends from the inner surface 124A of the first bracket 120A to the inner surface 124B of the second bracket 120B. As illustrated in FIG. 3A (top view) and FIG. 3B (front view), the exercise assembly crossbar 142 is affixed to the first and second brackets 120A/120B, e.g. to the inner surface 124A/124B of each of the first and second brackets. As used herein, the term “affixed” is to be broadly construed, and includes being attached using a fastener (e.g.,

a nail and/or screw), being affixed using an adhesive, and/or being inserted partially or completely through the planar bodies 122A and 122B. The assembly crossbar 142 illustrated in FIGS. 2A and 2B and in FIGS. 3A and 3B is affixed at a point approximately one-half way (e.g., one-half the distance) between the lower vertical support notch 136A/136B and the upper vertical support notch 138A/138B, e.g., at a midpoint. However, the exercise assembly crossbar 142 may be offset from the midpoint between the notches, e.g., as is illustrated in FIG. 1 where the assembly crossbar 142 is placed nearer the upper notches 140A/140B. To facilitate use during exercise, the exercise assembly crossbar 142 may have a substantially circular cross-section, e.g., in the form of a cylindrical dowel or rod, although other cross-sections such as a polygonal (e.g., rectangular) may also be utilized.

In the embodiment illustrated in FIGS. 1 to 3, the crossbar assembly 110 also includes a horizontal plank 144 extending along the back side of the assembly, e.g., extending from the first bracket 120A to the second bracket 120B. The horizontal plank 144 is affixed to each of the first and second brackets 120A/120B at or near the top edge 128A/128B and at or near the back edge 134A/134B of the first and second brackets. As is described below, the plank 144 may advantageously provide a planar surface against which a participant can push (e.g., for a resistance-based exercise), as opposed to pushing against a round crossbar.

As illustrated in FIGS. 1 to 3, first and second securement flaps 180A/180B are pivotally connected to the first horizontally spaced-apart brackets 120A/120B respectively, e.g., to the top edges 128A/128B of the planar bodies 122A/122B. The first and second securement flaps 180A/180B each include a securement notch 182A/182B disposed in top edges 188A/188B of the securement flaps. The securement notches 182A/182B are configured, e.g., sized and shaped, to operatively engage an exercise ladder crossbar when the securement flaps 180A/180B are pivoted upwardly. See FIGS. 4 to 6 below. In this regard, the securement flaps 180A/180B are pivotably connected to the respective brackets 120A/120B. The pivotable connection may be implemented using a variety of mechanisms including different types of hinges such as barrel hinges, spring hinges, butt hinges and the like. As illustrated in FIGS. 1 to 3, the pivotable connection is implemented using one or more hidden barrel hinges that are disposed in the top edges 128A/128B of the planar bodies 122A/122B and the bottom edges of the securement flaps 180A/180B.

The crossbar assembly 110 (e.g., the brackets, the crossbar, the plank and the securement hinges) may be fabricated from a variety of materials such as plastics, composite materials, etc., and in one embodiment is primarily fabricated from wood. Further, different components may be fabricated from different materials if desired.

FIGS. 4 to 6 illustrate an exercise ladder arrangement 160 incorporating a removable crossbar assembly 110 to facilitate use of the exercise ladder 162, e.g., to provide an intermediate crossbar height between two fixed crossbars on the exercise ladder 162. As illustrated in FIGS. 4 to 6, the exercise ladder 162 includes first and second spaced-apart vertical supports 164A/164B and a plurality of fixed exercise crossbars (e.g., adjacent crossbars 166A and 166B) extending between and affixed to the first and second vertical supports 164A/164B. The exercise crossbars 166A/166B have a substantially circular cross-section, e.g., to provide a comfortable gripping surface for an exercise participant. A removable crossbar assembly 110 is secured to the exercise ladder 162, i.e., is secured to crossbars 166A/166B by placing the lower attachment notches onto the lower cross-

bar 166B and the upper attachment notches onto the upper crossbar 164A, e.g., by passing the crossbar 166A through the gaps 140A/140B to engage the notches 138A/138B. The removable assembly is configured substantially as illustrated in FIGS. 1 to 3 and includes first and second horizontally spaced-apart brackets 120A/120B as described above for securing the assembly 110 to the ladder 162. As illustrated in FIGS. 1 to 3, the notches 136A/136B and 138A/138B include curved inner surfaces for receiving the circular (e.g., cylindrical) exercise crossbars therein.

As illustrated in FIG. 4, the exercise ladder 162 may be associated with other devices such as the exercise device 190, which includes two platforms that are movable along parallel tracks. Such a device is illustrated in U.S. Pat. No. 7,931,570 by Hoffman and U.S. Design Pat. No. D622,787 by Masterson et al., each of which is incorporated herein by reference in its entirety. As can be seen in FIG. 4, the removable crossbar assembly 110 enables the assembly crossbar 142 to be located at positions (e.g., heights) that are not obtainable with the fixed crossbars on the exercise ladder 162. By way of example, the fixed crossbars may be spaced at intervals of about 8 inches. The removable crossbar assembly 110 therefore enables the participant to select a height at 4-inch intervals rather than 8-inch intervals, and more closely align with the exercise participant's shoulder height, for example.

As best illustrated in FIG. 5, the assembly 110 has a width, e.g., the distance between the outer surfaces of the brackets 122A/122B, that is substantially the same as the interior width of the exercise ladder 162, e.g., the distance between inner surfaces of the vertical supports 164A/164B. For example, the width of the crossbar assembly 110 may be such that the outer surfaces of the brackets 124A/124B are in contact with the inner surfaces of the vertical supports 164A/164B. In this manner, the crossbar assembly 110 is restricted from horizontal movement during use. Alternatively, and as illustrated below, the crossbar assembly 110 may have a smaller width and one or more spacer elements may be placed on a fixed crossbar to restrict horizontal movement of the crossbar assembly 110, as is described below.

As is illustrated in FIGS. 4 to 6, securement flaps 180A/180B are pivoted upwardly, e.g., into a vertical orientation that is co-planar with the planar bodies 122A/122B. When pivoted upwardly in this manner, the securement notches 182A/182B engage with the third exercise ladder crossbar 166C that is disposed above the second exercise ladder crossbar 166A. For example, the height of the securement flaps 180A/180B may be selected in combination with the depth of the securement notches 182A/182B such that the bottom edges of the securement notches 182A/182B are in contact with the third exercise ladder crossbar 166C, e.g., with the bottom surface of the third exercise ladder crossbar 166C. For example, the securement notches 182A/182B may be configured, e.g., sized and shaped, to engage with the bottom half of the third exercise ladder crossbar 166C. In this manner, the securement flaps 180A/180B reduce or prevent vertical movement of the removable crossbar assembly 110 during use. To remove the crossbar assembly 110 from the exercise ladder, a user simply pivots the securement flaps 180A/180B downwardly to disengage the securement notches 182A/182B from the third exercise ladder crossbar 166C.

FIG. 7 and FIGS. 8A and 8B illustrate another embodiment of a removable crossbar attachment and FIGS. 9 to 11 illustrate an exercise ladder arrangement incorporating the removable crossbar assembly. As illustrated in FIG. 7 and

FIGS. 8A and 8B, the removable crossbar assembly 710 includes many similar features as the removable crossbar assembly illustrated in FIGS. 1 to 3 above. Thus, the crossbar assembly 710 includes a first bracket 720A and a second bracket 720B that is spaced away from (e.g., horizontally spaced-away from) the first bracket 720A. The brackets 720A/720B are configured to be operatively attached to an exercise ladder (FIGS. 9 to 11) to secure the removable attachment to the exercise ladder. The brackets 720A/720B each include a planar body 722A/722B into which notches, or functionally similar features, are formed to facilitate the securing of the assembly 710 to the exercise ladder.

As with the embodiment of FIGS. 1 to 3, each of the planar bodies includes an inner surface 724A/724B and an outer surface 726A/726B, each surface bounded by a top edge 728A/728B, a bottom edge 730A/730B, a front edge 732A/732B and a back edge 734A/734B. A lower vertical support notch 736A/736B is formed in the bottom edge and is configured (e.g. sized and shaped) to receive a first (lower) exercise ladder crossbar therein. An upper vertical support notch 738A/738B is formed in the planar body, above and substantially vertically colinear with the lower vertical support notch 736A/736B as shown in FIGS. 8A and 8B. The upper vertical support notch 738A/738B is configured (e.g., sized and shaped) to receive a second (upper) exercise ladder crossbar therein, e.g., a second exercise crossbar that is adjacent to and spaced apart (e.g. vertically spaced-apart) from the first exercise bar. A gap 740A/740B is formed in the back edge 734A/734B of the planar body and extends to (e.g., enables access to) the upper vertical support notch 738A/738B to enable the second exercise ladder crossbar to be placed through the gap 740A/740B and into the upper vertical support notch 738A/738B, e.g., without necessitating removal of a crossbar from the exercise ladder.

An exercise assembly crossbar 742 extends across the assembly, e.g., extends from the inner surface 724A of the first bracket 720A to the inner surface 724B of the second bracket 720B. The exercise crossbar 742 is affixed to first and second brackets at a point approximately one-half way between the lower vertical support notch 736A/736B and the upper vertical support notch 738A/738B, although the exercise crossbar 742 may be affixed to the brackets 720A/720B at other positions.

The crossbar assembly 710 also includes a horizontal plank 744 extending along a back side of the attachment, e.g., extending from the first bracket 720A to the second bracket 720B. The horizontal plank 744 is affixed to each of the first and second brackets 720A/720B near the top edge 728A/728B and the back edge 734A/734B of the first and second brackets.

In the embodiment illustrated in FIGS. 7 and 8, each bracket 720A/720B also includes a brace 750A/750B extending from the front edge 732A/732B of the planar body 722A/722B. The braces 750A/750B have a top edge 752A/752B that includes an exercise device receiving notch 754A/754B disposed along the top edge. The exercise device receiving notches 754A/754B are configured (e.g., sized and shaped) to receive and secure an independent exercise device, e.g., having a bar that is sized and shaped to be secured in the notches 754A/754B in spaced-away relation from the front edges 732A/732B of the brackets 720A/720B. The device receiving notches 754A/754B may be substantially vertically coplanar with the attachment exercise crossbar 742, e.g. so that the crossbar and the piece of exercise equipment placed in the equipment notches 754A/754B are disposed at about the same height as shown in FIGS. 8A and

8B. The braces 750A/750B may be integrally formed with the brackets 720A/720B, e.g., fabricated from a single piece of material, such as from wood.

As illustrated in FIGS. 7, 8A and 8B, first and second securement flaps 780A/780B are pivotally connected to the first horizontally spaced-apart brackets 720A/720B respectively, e.g., to the top edges 728A/728B of the planar bodies 722A/722B. The first and second securement flaps 780A/780B each include a securement notch 782A/782B disposed in top edges 788A/788B of the securement flaps. The securement notches 782A/782B are configured, e.g., sized and shaped, to operatively engage an exercise ladder crossbar when the securement flaps 780A/780B are pivoted upwardly. In this regard, the securement flaps 780A/780B are pivotably connected to the respective brackets 720A/720B. As with the embodiments illustrated above, the pivotable connection may be implemented using a variety of mechanisms including different types of hinges such as barrel hinges, spring hinges, butt hinges and the like. As illustrated in FIG. 7, the pivotable connection is implemented using one or more hidden barrel hinges that are disposed in the top edges 728A/728B of the planar bodies 722A/722B and the bottom edges of the securement flaps.

FIGS. 8A and 8B also illustrate first and second removable locking pins 794A/794B that are inserted through the braces 750A/750B and across the top of the device receiving notches 754A/754B, e.g., to secure a device within the device receiving notches 754A/754B. See FIG. 10.

As illustrated in FIG. 9, the assembly 710 may be secured to an exercise ladder by placing the lower vertical support notches 736A/736B onto a first fixed exercise crossbar 766B and the upper vertical support notches 738A/738B onto a second fixed exercise crossbar 766A that is adjacent to and above the first exercise crossbar 766B. The notches 736A/736B and 738A/738B include curved surfaces for receiving the circular (e.g., cylindrical) exercise crossbars therein. Spacer elements (e.g., spacer elements 770A/770B) may be placed onto at least one of the fixed crossbars to deter horizontal movement of the crossbar assembly 710. For example, the spacer elements 770A/770B may be pliable sleeves (e.g. foam sleeves) having a slit along a length of the sleeve to enable the sleeve to be easily placed onto a crossbar.

Securement flaps 780A/780B are pivoted upwardly, e.g., into a vertical orientation that is co-planar with the planar bodies 722A/722B. When pivoted upwardly in this manner, the securement notches 782A/782B engage with the third exercise ladder crossbar 766C that is disposed above the second exercise ladder crossbar 766A. As with the embodiment illustrated in FIG. 5, the height of the securement flaps 780A/780B may be selected in combination with the depth of the securement notches 782A/782B such that the bottom edges of the securement notches 782A/782B are in contact with the third exercise ladder crossbar 766C, e.g., with the bottom surface of the third exercise ladder crossbar 766C. For example, the securement notches 782A/782B may be configured, e.g., sized and shaped, to engage with the bottom half of the third exercise ladder crossbar 766C. In this manner, the securement flaps 780A/780B reduce or prevent vertical movement of the removable crossbar assembly 710 during use. To remove the crossbar assembly 710 from the exercise ladder, a user simply pivots the securement flaps 780A/780B downwardly to disengage the securement notches 782A/782B from the third exercise ladder crossbar 766C.

FIG. 10 illustrates the assembly of FIG. 9 with an exercise device 792 (e.g., a resistance exercise device) secured to the

assembly 710. The exercise device 780 illustrated in FIG. 10 is a MOTR® device distributed by Balanced Body, Inc. of Sacramento, CA. See U.S. Pat. No. 8,029,425 by Bronston et al. and U.S. Design Pat. No. D667,899 by Bronston et al., each of which is incorporated herein by reference in its entirety. It will be appreciated that other types of exercise devices may be operatively secured to the assembly 710 as desired, e.g., by being placed within the equipment notches 754A/754B disposed within the braces 750A/750B. As illustrated in FIG. 10, removable locking pins 794A/794B secure the exercise device 792 within the device receiving notches 754A/754B.

Although the foregoing description and the attached figures illustrate a lower vertical support notch disposed in a bottom edge of the brackets, it will be appreciated that the lower notch may be configured in manner similar to the upper vertical support notch. That is, the lower notch may be accessible via a gap in the back edge of the bracket.

While various embodiments of a crossbar assembly and an exercise arrangement have been described in detail, it is apparent that modifications and adaptations of those embodiments will occur to those skilled in the art. However, it is to be expressly understood that such modifications and adaptations are within the spirit and scope of the present disclosure.

What is claimed is:

1. A removable crossbar assembly for use with an exercise ladder comprising a plurality of spaced-apart exercise ladder crossbars, comprising:
  - first and second horizontally spaced-apart brackets, the first and second brackets each comprising,
    - a planar body having an inner surface and an outer surface, each surface bounded by a top edge, a bottom edge, a front edge and a back edge,
    - a lower vertical support notch formed in the planar body and configured to receive a first exercise ladder crossbar therein,
    - an upper vertical support notch formed in the planar body, above and substantially vertically colinear with the lower vertical support notch, and configured to receive a second exercise ladder crossbar therein;
    - an exercise crossbar extending from the first bracket to the second bracket, wherein the exercise crossbar is affixed to each of the first and second brackets between the lower vertical support notch and the upper vertical support notch;
    - a first securement flap pivotally connected to the first horizontally spaced-apart bracket planar body and comprising a first securement notch disposed in a top edge of the first securement flap, wherein the first securement notch is configured to operatively engage an exercise ladder crossbar when the first securement flap is pivoted upwardly; and
    - a second securement flap pivotally connected to the second horizontally spaced-apart bracket planar body and comprising a second securement notch disposed in a top edge of the second securement flap, wherein the second securement notch is configured to operatively engage the exercise ladder crossbar when the second securement flap is pivoted upwardly.
  - 2. The crossbar assembly recited in claim 1, wherein the lower vertical support notch is formed in the bottom edge of the planar bodies.
  - 3. The crossbar assembly recited in claim 1, wherein the upper vertical support notch is accessed through a gap formed in the back edge of the planar bodies.

4. The crossbar assembly recited in claim 1, wherein the exercise crossbar is affixed between the first bracket and the second bracket at a point approximately one-half way between the upper vertical support notches and the lower vertical support notches.

5. The crossbar assembly recited in claim 1, further comprising:

a horizontal plank extending from the first bracket to the second bracket, wherein the horizontal plank is affixed to each of the first and second brackets near the top edge and the back edge of the first and second brackets.

6. The crossbar assembly recited in claim 1, wherein each of the first and second brackets further comprises:

a brace extending outwardly from the front edge of the planar body, the brace comprising an exercise equipment receiving notch.

7. The crossbar assembly recited in claim 6, wherein the exercise equipment receiving notch is disposed in a top edge of the brace.

8. The crossbar assembly recited in claim 7, wherein the exercise equipment receiving notch is spaced away from the front edge of the first and second brackets.

9. The crossbar assembly recited in claim 6, wherein the exercise equipment receiving notch is substantially vertically coplanar with the attachment exercise crossbar.

10. The crossbar assembly recited in claim 1, wherein the first and second securement flaps are pivotally connected to the top edges of the first and second horizontally spaced-apart bracket planar bodies respectively.

11. The crossbar assembly recited in claim 1, wherein the first and second securement flaps are pivotally connected to the top edges of the first and second horizontally spaced-apart bracket planar bodies respectively using at least a first barrel hinge.

12. An exercise ladder arrangement, comprising:

- an exercise ladder comprising first and second spaced-apart vertical supports and at least three exercise ladder crossbars extending between and affixed to the first and second vertical supports;
- a crossbar assembly removably secured to the exercise ladder, the crossbar assembly comprising,

first and second horizontally spaced-apart brackets, the first and second brackets each comprising,

- a planar body having an inner surface and an outer surface, each surface bounded by a top edge, a bottom edge, a front edge and a back edge,
- a lower vertical support notch securing a first exercise ladder crossbar therein, and

an upper vertical support notch formed in the planar body, above and substantially vertically colinear with the lower vertical support notch, and securing a second exercise ladder crossbar therein;

an exercise assembly crossbar extending from the first bracket to the second bracket, wherein the exercise assembly crossbar is affixed to each of the first and second brackets;

a first securement flap pivotally connected to the first horizontally spaced-apart bracket planar body and comprising a first securement notch disposed in a top edge of the first securement flap, wherein the first securement notch is configured to operatively engage a third exercise ladder crossbar when the first securement flap is pivoted upwardly; and

a second securement flap pivotally connected to the second horizontally spaced-apart bracket planar body and comprising a second securement notch disposed in a top edge of the second securement flap,

11

wherein the second securement notch is configured to operatively engage the third exercise ladder crossbar when the second securement flap is pivoted upwardly.

13. The exercise ladder arrangement recited in claim **12**, wherein the exercise assembly crossbar is affixed to each of the first and second brackets at a point approximately one-half the distance between the lower vertical support notch and the upper vertical support notch.

14. The exercise ladder arrangement recited in claim **12**, further comprising:

a horizontal plank extending from the first bracket to the second bracket, wherein the horizontal plank is affixed to each of the first and second brackets near the top edge and the back edge of the first and second brackets.

15. The exercise ladder arrangement recited in claim **12**, wherein each of the first and second brackets further comprises:

a brace extending from the front edge of the planar body, the brace comprising an equipment receiving notch disposed therein.

12

16. The exercise ladder arrangement recited in claim **15**, wherein the equipment notches are formed in a top edge of the brace.

17. The exercise ladder arrangement recited in claim **16**, wherein the equipment receiving notch is spaced away from the front edge of the first and second brackets.

18. The exercise ladder arrangement recited in claim **15**, wherein the equipment receiving notch is substantially vertically coplanar with the attachment exercise crossbar.

19. The exercise ladder arrangement recited in claim **15**, further comprising:

first and second locking pins disposed in each brace extending from the front edge of the planar body of the first and second brackets, wherein the locking pins are configured to secure a piece of equipment in the equipment receiving notches disposed therein.

20. The exercise ladder arrangement recited in claim **12**, further comprising:

at least a first spacer element disposed on at least one of the first and second exercise ladder crossbars between the vertical ladder support and the removable exercise assembly.
